UNITED STATES PATENT OFFICE

GUSTAVE A. UNGAR, OF PELHAM MANOR, NEW YORK, ASSIGNOR TO COMMERCIAL PATENTS INCORPORATED, OF NEW YORK, N. Y., A CORPORATION OF NEW YORK

FLUID APPARATUS PROVIDED WITH COOPERATING ROTARY PISTONS

Application filed June 11, 1930. Serial No. 460,309.

My invention relates to pumps and other apparatus through which a fluid is caused to pass, and more particularly to apparatus of the type provided with co-operating rotary pistons. In apparatus of this type as constructed hitherto, all cross sections of the piston taken in planes perpendicular to the axis of rotation, at different points of such axis, cut the outline or periphery of the piston in profile lines which are similar, for each such cross section, both as to shape and position; or, to express this differently, successive longitudinal or axial sections of the piston as constructed hitherto, cut the outline or periphery of the piston along lines of the same shape, generally (when the peripheries of the pistons are cylindrical, in the broad mathematical sense of the term) straight lines parallel to the axis. With these prior constructions, rotation of the pistons at a constant angular velocity has corresponded to considerable irregularities in the rate of the flow of the fluid through the apparatus. Such irregularities will occur with pistons which are cylindrical in the mathematical sense (or "straight" pistons, as they may be called, since their peripheral surfaces may be generated by the motion of a straight line), whatever profile such pistons may have. The irregularities or fluctuations will increase with an increase in the ratio between the greatest and the smallest radius of the said peripheral surface. The object of my present invention is to remedy this drawback and to obtain a condition in which a practically uniform rate of flow of the fluid will correspond to a constant angular velocity of the pistons.

For this purpose, I have devised a construction in which cross sections taken through a piston at successive points of its axis of rotation, will vary gradually from one end of the piston to the other, and in which successive axial sections of the piston likewise will cut the outline or periphery of the piston along varying lines.

Several satisfactory examples of my invention are shown, as examples, in the accompanying drawings, in which Fig. 1 shows one form of my invention in axial section, on line 1—1 of Fig. 2, the latter being a diagram-

matic cross section, substantially on line 2—2 of Fig. 1; Fig. 3 is a diagrammatic end view of one of the pistons shown in Fig. 2, and Fig. 4 is a corresponding side view, with a representation of the helical or spiral path of a point at which the two pistons come in contact; Figs. 5 and 6 are diagrams showing two different positions of narrow or differential slices of co-operating pistons which have an irregular output when rotating at a constant angular speed; Figs. 7, 8 and 8^a are diagrammatic views, hereinafter referred to, showing that a uniform output is obtained with my invention; Fig. 8^b is a section substantially on line 8^b—8^b of Fig. 7; Fig. 9 is an axial section, and Fig. 10 is a cross section illustrating a second embodiment of my invention; Fig. 11 is a cross section of a third embodiment; Fig. 12 is a plan view of another form of piston embodying my invention; Fig. 13 is a developed view illustrating the piston shown in Fig. 12 in conjunction with a mating piston; Figs. 14, 15 and 16 are cross sections on the planes indicated by the lines 14—14, 15—15, and 16—16 respectively of Figs. 12 and 13; and Fig. 17 is a diagram illustrating the operation of the construction shown in Figs. 12 to 16.

In Figs. 2 and 10, I indicates the inlet and O the outlet of the casing C having two cylindrical chambers concentric with the parallel shafts S, S' of the rotary pistons P, P', shown as of similar construction, except that one of them is right-hand and the other left-hand, as explained hereinafter. These pistons are adapted to rotate in opposite directions at equal angular velocities, as by mounting on the shafts S, S', spur gears G, G' of equal diameters. Each piston has end faces of approximately elliptical or oval shape, the major axis of the ellipse or oval being approximately equal to the diameter of the chamber in which the piston rotates. The end faces of the same piston are alike in shape, but differ in their relative position, the major axis of one end being in a position at 90° from the major axis of the other end, as will be seen best in Fig. 2. The minor radius (half-axis) of the ellipse or oval is obtained by subtracting the major radius 100

from the distance separating the centers of the shafts S, S' . The piston portion between its ends is of what may be termed of screw formation, that is to say, there is a gradual 5 twist from one end to the other, and any cross section of the piston (perpendicular to the axis of rotation) will be of the same oval shape as the ends, but with the axes of the ellipse shifting in position gradually as cross 10 sections are taken at successive points lengthwise of the axis of rotation. The twist is left-hand for one of the pistons (say the lower piston P'), and right-hand for the other.

15 In practice, I prefer that the pistons P, P' should not come into actual contact, but leave a small clearance between the points of closest approach. This clearance will be constant in all positions of the pistons, and 20 the line of contact, or rather of closest approach, will at all times be continuous from one end face of the pistons to the other; thus there will at no time be any direct communication, or by-pass, between the inlet I and 25 the outlet O , but the fluid has to follow an arcuate path along the inner walls of the casing chambers during the rotation of the pistons.

It will be noted from Figs. 2, 10 and 11 30 that the inlet I and the outlet O are diametrically opposite each other, and these inlet and outlet ports or connections may extend practically the full length of the pistons, as clearly indicated by the dotted rectangles in Figs. 1 and 8^b. The flow of the 35 fluid both to the interior of the casing C and away therefrom, will be substantially radial and circumferential, and will not be axial as it is in certain prior devices.

40 If the pistons were made of approximately oval cross section, but without the longitudinal twist or screw formation described above (that is, if the pistons were shaped as oval or elliptical cylinders), the rate of the 45 flow of the fluid, with a constant angular velocity of the pistons, would not be uniform but attain a minimum when the major axes of the two ellipses are perpendicular to each other (Fig. 5), and a maximum when they 50 are parallel to each other (Fig. 6). These minima occur in piston positions 90° apart, while the maxima occur in positions at 45° from the minima positions. This inequality in 55 the rate of flow with pistons shaped as elliptical cylinders, increases with the eccentricity of the ellipse, or in other words, with the difference between the radii of the ellipse. The uneven rate of flow, at a constant angular velocity of the pistons, will be understood best 60 by a consideration of the diagrammatic Figs. 5 and 6. Fig. 5 shows the pistons A, B or slices perpendicular to the axis of rotation in a position in which their major axes are perpendicular to each other, it being understood 65 that these pistons or slices have no twist

such as those described with reference to Figs. 1 and 2. If the pistons A, B rotate through an angle ϑ , the output or delivery of piston A will momentarily be nil, since the point of contact or of closest approach of the two pistons is at a circular arc of minimum radius. The output or delivery of piston B will be a zone sector, within the angle ϑ , the inner radius r of said sector being the minimum radius of the piston profile, and the outer radius R of said zone being the maximum radius of said profile. Let us designate the area of said zone sector as D , and this indicates the pump output or delivery in the position shown in Fig. 5. When the pistons A, B are in a position in which their major axes are parallel, as in Fig. 6, their rotation through the same angle ϑ will produce an output or delivery equal to $D' + D^2$, each of these two areas D' and D^2 being a zone sector, within 75 the angle ϑ , the inner radius of such sector being equal to the arithmetical mean, 80

$$\frac{R+r}{2}$$

90 of the maximum radius R and the minimum radius r , while the outer radius of the sector is equal to the maximum radius R . Comparing the equal areas of the sectors D' and D^2 with the area of the sector D , it will be obvious; since the sector D narrows uniformly toward its inner end, that the outer portions D', D^2 are of larger area than the inner portions indicated at D^3 . In other words, each area D' or D^2 is greater than one-half of the entire sector area D , and consequently, $D' + D^2 > D$. Thus, rotation of the pistons A, B through the same angle ϑ will produce a smaller (minimum) pump delivery D in the vicinity of the position Fig. 5, and a greater (maximum) pump delivery $D' + D^2$ in the vicinity of the position Fig. 6. In positions intermediate between those shown in Figs. 5 and 6, the output or rate of flow will have a gradually changing intermediate value. It will thus be evident that with straight or cylindrical pistons or slices (Figs. 5 and 6), the rate of flow will not be uniform when the pistons are rotated at a constant angular velocity, but will fluctuate between a maximum and a minimum, which are attained in piston positions 45° apart. This fluctuation increases with increase in the ratio 100

$$\frac{R}{r}$$

110 The inequalities in the rate of flow, at constant angular velocities of the pistons, are overcome or compensated perfectly by giving the pistons the shape of screws having a lead of 90° from one end to the other, as mentioned above. This will be understood best from a consideration of the diagrammatic Figs. 3 and 4. Fig. 3 shows the piston P' in the same position as Fig. 2, the point of contact with, 115 or of closest approach to, the other piston (not 120

shown in this view) being indicated at Y. If we consider a position 90° before reaching the one shown in Fig. 4, the point of piston P' at which it was in contact with, or closest to, the other piston, would be the one indicated at X. The points X and Y are at equal distances (R) from the center or axis of the piston, but at opposite ends of the piston, as will be evident from Fig. 4. Thus, during the rotation of the piston through an angle of 90° , the shifting point of contact, or of closest approach, of the two pistons would describe, on the piston P', a helical line X, Y. In other words, such point of contact or of closest approach will shift from one end of the piston to the other, during rotation through an angle of 90° , and back to the first-mentioned end, during the rotation through the next 90° . The path of the point of contact, or of closest approach, on the other piston, would be similar to the one illustrated, except that the helix would run in the opposite direction. Fig. 4 also illustrates the extension of the helical line Y X through Y', X', Y'' to the full 360° , showing that L, the lead of pitch of the said helical line, equals four times the width W of the piston body.

With the twisted form of piston explained in connection with Figs. 3 and 4, the rate of flow at constant angular speed of rotation is no longer fluctuating as in the slices shown in Figs. 5 and 6, but practically uniform, since, as will also appear from Fig. 1, the pistons P, P', considered in axial section, have their active surfaces closer to their respective axes of rotation at one end of the piston than at the other, and this relation is reversed for the two pistons. Thus in Fig. 1 the active surface at the right-hand end of piston P is closer to the axis of rotation than the one at the left-hand end, while the active surface of piston P' is closer to the axis of rotation at the left-hand end of the piston than at the right-hand end. At each moment therefore, the sum or integral of the deliveries made by all the narrow zones or slices of the pistons (slices perpendicular to the axes of rotation) will be constant, and therefore the output of the pump will be constant when the pistons P, P' rotate at a constant angular velocity.

Figs. 7, 8 and 8^a further illustrate these conditions, Fig. 7 showing the pistons P, P' in a position in which their major axes are parallel (45° from the position shown in Fig. 2). Within the angles α , the piston outline (in end view or cross section) is a circular arc, and the corresponding helical bands c, c' are portions of circular cylinders, the inner bands c being portions of a circular cylinder with the radius r, while the outer bands c' are portions of a circular cylinder with the radius R. The provision of cylindrical surface portions as at c and c', is of advantage in that it enables me to preserve

at all times, adjacent to the inlet I and the outlet O, a sufficient amount of overlap L to insure an efficient seal at these points and to prevent any short-circuiting or direct flow from the inlet I to the outlet O. The intermediate portions c'' of the outer or active piston surfaces are twisted, or non-cylindrical. The diagram Fig. 8 shows a development of the piston circumference, and (at the right) a developed profile of the rotor or piston. Fig. 8^a is a diagram illustrating the fluid delivery of the two pistons in the longitudinal plane indicated at x-x in Fig. 8. While within such plane the delivery, or rate of flow, varies, the sum or integral of all the amounts delivered at all points of the pistons, from one end to the other, is constant, and the rate of flow of the pump, as a whole, therefore is constant.

A section (such as Fig. 8^b) taken through the axes of both pistons when the major axes of their corresponding elliptical end faces are parallel, will show the line of contact, or of closest approach, as a curve symmetrical to a plane parallel to said end faces and midway between them. A section (Fig. 1) taken through the axes of both pistons when the major axes of their corresponding elliptical end faces are perpendicular to each other, will show the line of contact, or of closest approach, as a reverse curve one end of which is nearer to the axis of one piston than the other end. If transverse sections were taken in positions of the pistons intermediate between those just referred to, they would show a gradual transition in the longitudinal shape of the line of contact, or of closest approach.

As a variant of the one-piece pistons the outlines of which have a continuous twist or screw-shape from one end to the other, I have devised a construction of such pistons in cylindrical laminations or slices alike in shape, but secured together to form an approximation to the screw-shape shown in Figs. 1 to 4. Such approximation can be increased by using a greater number of slices, of correspondingly reduced thickness. Figs. 9 and 10 illustrate this construction of built-up pistons. Each of the slices p or p' is of the same shape, viz. that of a thin plate or slice of the form of an approximate elliptical or oval cylinder, and can be manufactured readily by stamping sheet metal, or other inexpensive methods. The individual plates or laminations of the same pistons are of equal thickness, and would be set in positions shifted or displaced angularly to each other, by equal amounts, in such a manner that the angular shifting of the last lamination relatively to the first will amount to 90° , in the particular case illustrated. The laminations may be held in the proper position in any suitable manner, for instance by means of a key passing through properly positioned keyways in the

successive laminations. If there are n laminations, the angular lead of each over its neighbor will be

$$5 \quad \frac{90^\circ}{n}$$

in the particular case referred to; for instance, with nine laminations, the angular lead, from one lamination to the next, will be 10 10° . It is true that, considering each lamination alone, the piston outline, within that lamination, will have the shape of an elliptical cylinder; yet the succession of these short elliptical cylinders, in somewhat step-like 15 arrangement, as shown, will form a close approximation to the exact theoretical twisted or screw-surface described in connection with the first form of my invention. In practice, especially with a large number of laminations, this built-up construction of pistons 20 will yield a virtually uniform rate of flow of the fluid, with a constant angular velocity of the pistons.

My invention is not restricted to pistons of 25 elliptical or oval outline, but various other shapes may be employed. The piston outline, however, should always be symmetrical to the axis of rotation, and selected so as to provide rolling of the profile of one piston on the 30 other, or with a constant clearance (i. e. without actual contact) when the two pistons are rotating in opposite directions with equal angular velocities. An example of such other shapes is shown in Fig. 11, where the piston 35 has a screw-shape, with a lead of 90° from one end to the other, as in Figs. 1 to 4 and 7 to 10, but the piston outline includes circular arcs a and a' (for instance of 30°) centered upon the axes of the respective pistons, 40 and suitable connecting portions b . With outlines formed partly of circular arcs, I am enabled to use circumferentially wider inlet and outlet openings at I and O respectively, but otherwise this form of my invention 45 has the same advantages as the constructions described above.

Still another form of my invention is shown in Figs. 12 to 17. Here cross sections taken through the same piston at different 50 points along its axis of rotation are not of like outline, as in the constructions described above, but such outline varies lengthwise of said axis. Yet, in this form also, I use a screw formation or longitudinal twist on certain portions of the co-operating piston outlines. Each piston p^2 , p^3 has cylindrical portions p^4 , p^5 respectively of circular cross section and of the same diameter, the axes of 55 these portions coinciding with the axes of the respective pistons. Each piston p^2 , p^3 furthermore has cylindrical portions p^6 , p^7 respectively, likewise of circular cross section, but of a diameter smaller than that of the portions p^4 , p^5 , and co-axial therewith. The 60 portions p^4 , p^6 and p^5 , p^7 are connected by

helical surfaces p^8 , p^9 respectively constituting as it were the flanks of teeth the outer faces of which are formed by the cylindrical portions p^4 , p^5 respectively. The helical portions p^8 , p^9 are of uniform pitch from one end 70 face of each piston to the other, and the lead is 90° from one end to the other, as in the forms described above. On one piston, the outer or relatively raised portions p^4 are of diamond shape in developed view (Fig. 13) 75 and the inner or relatively depressed portions p^6 are triangular, with their bases at the ends of the piston, and their apices at its median transverse plane. On the other piston, the arrangement is reversed, the triangular raised portions p^5 matching the depressed triangular portions p^6 of the other cylinder, while the diamond-shaped depressed portions p^7 match the like raised portions p^8 . It will be evident that the outline 80 of each piston, in successive cross sections taken along its axis of rotation, will vary gradually from one end of the piston to the other. The formation of the helical surfaces p^8 , p^9 is such that during the rotation of the two 85 pistons their points of contact, or of closest approach, will at all times form a continuous line from one end of the piston to the other.

Fig. 13 is a developed view, being virtually a section taken in the cylindrical surfaces 90 (pitch surfaces) indicated in Figs. 10, 11 and 12 by the dotted circles between those corresponding to the inner surfaces p^6 , p^7 and to the outer surfaces p^4 , p^5 respectively. The left half of Fig. 13 shows the piston p^2 , 1 and the right half shows the piston p^3 . It will be obvious that at any particular moment, the amount of fluid passing through the device will correspond to the sum or integral of all the minute quantities passing through the device at different points along the axis. The diagram Fig. 17 shows that the total flow of fluid through the device, at any particular moment, consists of the sum of three quantities: First, the quantity Q' at such points where the outer portion p^4 of the piston p^2 co-operates with the inner portion p^7 of the other piston p^3 ; second, the quantity Q^2 at such points where the inner portion p^6 of the piston p^2 co-operates with the outer portion p^5 of the other piston p^3 ; and third, the quantity Q^3 at those points where the helical portions of the two pistons co-operate. If we consider the slightly changed condition obtaining after the pistons have rotated through an angle φ , the relative contributions to the quantities Q' and Q^2 (Q^3 being constant) will have varied, but the total amount $Q = Q' + Q^2 + Q^3$ remains the same, thus showing that a uniform rate of flow corresponds to a constant angular velocity of the pistons.

The construction illustrated by Figs. 12 to 17 is what may be termed a device provided with rotary pistons each having two teeth of

a cross section varying lengthwise of the axis. This form of my invention might be carried out in other ways, as long as the sum of the individual flow quantities Q' , Q^2 , Q^3 5 remains constant, which will be the case when the flanks of the teeth form helical surfaces of constant pitch.

I desire it to be understood, however, that my invention is not limited to a construction 10 in which the pistons are each provided with two portions of large diameter and two portions of small diameter, or, in other words, with two teeth; the invention is applicable to constructions in which the piston has more 15 than two teeth or points, or portions of large diameter, and particularly to the form of pumps known as gear pumps, whose pistons resemble gear wheels.

In practice, the shaft of one of the co-operating pistons (in any embodiment of my invention) is extended so that power may be applied to the device when it is used as a pump or for similar purposes, or that power may 25 be taken from the device if it is driven by the flow of fluid.

The toothed form exemplified by Figs. 12 to 16 gears one piston to the other and enables me to dispense with gears such as shown at G G' in Fig. 1; yet even in connection with 30 this toothed form, I consider the employment of gears (corresponding to G, G') desirable, in order to prevent wear of the co-operating pistons.

I claim:

35 1. A fluid apparatus comprising a casing having an inlet and an outlet diametrically opposite to said inlet, and cooperating pistons mounted in said casing to rotate about axes located in a plane substantially perpendicular to the line joining the inlet and the outlet, said pistons having helical portions of substantially uniform pitch extending axially thereof, said inlet and outlet being substantially as wide as the axial length of said pistons, whereby a constant volume flow is obtained.

2. A fluid apparatus according to claim 1, in which the helical piston portions have a lead of 90° from one end of a piston to the 50 other.

3. A fluid apparatus according to claim 1, in which the piston is built up of laminations transverse to the axis of rotation, said laminations being of substantially elliptical outline of like shape, but with their axes shifted by equal angles from one lamination to the next, to produce a helical surface.

4. A fluid apparatus according to claim 1, in which the cross section of each piston has 55 an outline composed of circular arcs of two different radii and connecting portions between arcs of different radii.

In testimony whereof I have hereunto set my hand.

GUSTAVE A. UNGAR.
